RULES FOR PLAYING

- A. Implements
1. Indicator Stick
2. Different Color Checkers
- B. Directions
1. 2 to 6 persons or more may take part. (2) The indicator stick is thrown to decide the turn as following: Airplane, Motorcycle, Automobile, Train, Pony Express and Carriage.
3. Each player uses one of colored checkers. (4) Players in turn throw the indicator stick, then move checkers ahead or back in accordance therewith.
- C. Instructions
1. Each player starts at the lower left corner, space marked Hollywood.
2. Each player in turn advances his checker the number of spaces as shown by a throw of the indicator stick.
3. The player who first reaches the last stop, "Nation's Capital," is declared the winner.

GAME

Young Wo Kim, Santa Barbara, Calif.

Application May 15, 1933, Serial No. 671,216

1 Claim. (Cl. 273—134)

This invention is a game which may be played by young and old, may be easily learned and will furnish entertainment and instruction. The invention provides devices movable over a game-board by chance determination to follow a definite route, the winner of the game being the player who first reaches the designated goal.

The invention is illustrated in the accompanying drawing and will be hereinafter fully set forth and defined.

In the accompanying drawing:

Figure 1 is a plan view of a game-board devised for use in playing my improved game.

Figure 2 is a perspective view of a series of playing pieces or men employed in the game.

Figures 3 and 4 are perspective views showing different sides of indicators which are employed to govern the movements of the men shown in Figure 2.

The game-board 1 may be cardboard, wood or other material having sufficient durability and may be a single member, as shown, or may be formed in two or more sections joined in any convenient manner so that it may be folded when not in use, all of which will be readily understood. Upon the lower portion of the game-board are displayed explanations of certain characters which govern the playing of the game and also are rules for playing. The surface of the board is divided by border and cross lines 2 and 3 into spaces which cover the entire playing field, these spaces being preferably rectangular, as shown. The spaces are numbered consecutively from one to forty-nine and in the upper portion of each space is a panel 4 containing the name of some city or other place of interest within the United States or its dependencies, the space numbered "1" at the lower left-hand corner of the board displaying the name "Hollywood", while the space numbered "49" at the center of the right-hand side of the board is labeled "Nation's Capitol". Within each space, except the space 49, are certain letters, as shown at 5, and opposite each letter in each space is one of the names given to one of the other spaces on the board. The letters 5 also appear in a panel 6 on the lower portion of the board and aligned with the respective letters are words explaining their significance. Thus C. indicates "carriage", P. indicates "pony-express", T. indicates "train", A. indicates "automobile", M. indicates "motor-cycle" and A. P. indicates "aeroplane", it thus being seen that various types of traffic mechanisms are symbolized upon the board and in the playing of the game.

The apparatus of the game also includes one or more movement indicators or lot devices 7, shown in Figures 3 and 4. Preferably each device consists of a stick having a hexagonal cross section and having displayed upon each face one of the modes of travel indicated on the panel 6, together with the initial or letter representing such mode of travel. The players are each provided with a playing piece or man 8, shown in Figure 2, and these men or playing pieces have distinctive colors so that when they are placed upon the game-board confusion as to the position of each player in the game will be avoided.

In playing the game, the players in turn will toss one of the sticks or chance devices 7 upon the board or upon a table upon which the board may be placed and will move his man accordingly to the legend which appears on the upper side of the stick when it comes to rest. For instance, in Figure 3 "pony-express" appears at 20 the top of the stick and in Figure 4 "motor-cycle" appears at the top of the stick. Each player at the start of the game will place his man upon the square or space No. 1, which is the starting point of the game. Assuming that the player has tossed the stick 7 so that it comes to the position as shown in Figure 3, the player will consult the legends in the space No. 1 and will find that aligned with the letter P. indicating "pony-express" is the designation "Yosemite Valley". He will thus be entitled to move his man forward to the space No. 4 which bears the title "Yosemite Valley" and each player in turn will toss the chance device and move his man accordingly to the legend displayed when the device 25 comes to rest. It will be noted that in panel No. 1 there is no reference to panel No. 2 so that no player will advance a degree from the area or space No. 1 to the second space but in space No. 9, which is labeled "Devil's Lake", he will find 30 opposite the letters A. P. "back to Catalina Island" so that the player whose movements bring his man to "Devil's Lake" will be obliged to return to the second area labeled "Catalina Island". A like reverse movement will be indicated upon other of the panels as will be seen from a study of the drawing. It will also be noted that in the space or area No. 2 there are five legends "no advance" and a player who tosses the chance device so that the corresponding letters are displayed at the top of the device will be obliged to retain his man in the second space without advancing. The space No. 49 is labeled 35 "Nation's Capitol" and is the end of the game, the player first moving his man over the pre- 40 45 50 55

scribed path, and according to the indications of the chance device, reaching the space No. 49 being the winner of the game.

The path to be followed by the men is not only indicated by the arrangement of the numbers on the panels but is also defined by a heavy line 9 which is disposed along the boundaries between adjacent panels so that the player must move his man always at the outerside of this line.

10 In the present illustration the game has been shown as embodying places of geographical interest but it will, of course, be understood that it may be built around other elements. The implements necessary for playing the game are 15 very simple and inexpensive and the game may be readily understood by anyone so that it may be played by any number of persons. Through playing the game the players will be made acquainted with at least the names of points in the

United States or in its dependencies of a general scenic or historic interest so that it will provide a mild means of education.

Having described the invention, I claim:

A game apparatus comprising a game board 5 having a surface divided into panels bearing a sequential relation to each other, a path defining a line impressed upon borders of abutting panels, each of said panels having an identifying designation and also being numbered to indicate its 10 position in the sequence in which the game is played and also bearing code characters indicative of transfer and extent thereof to other panels, and chance devices including sticks having polygonal cross sections presenting faces 15 bearing code characters similar to the code characters of said panels.
